SET-WORKS GRIPPING DEVICE.

1,189,563.

Specification of Letters Patent.

Patented July 4, 1916.

Application filed November 25, 1912. Serial No. 733,564.

To all whom it may concern:

Be it known that I, LEMUEL D. HANFORD, a citizen of the United States, residing at Milwaukee, in the county of Milwaukee and 5 State of Wisconsin, have invented a certain new and useful Improvement in Set-Works Gripping Devices, of which the following is a specification.

This invention relates to improvements 10 in the construction of set-works for saw-mills, and particularly to gripping devices adapted for use in that class of set-works in which the setting is performed by hand power.

15 An object of the invention is to provide a gripping device for hand-power set-works which is simple in construction and efficient in operation.

Another object is to provide a mechanism 20 which is more durable and accurate in its operation than similar devices of the prior art have been.

These results are accomplished generally 25 in the device of the present invention by improving and strengthening the various elements so that the possibility of excessive wear with its resulting lost motion, is practically eliminated.

Still another object of the invention is to 30 provide a device in which the parts which are subject to greatest wear are accessible and readily removable.

A clear conception of an embodiment of 35 the invention may be had by referring to the drawing accompanying and forming part of this specification in which like reference characters designate the same or similar parts in the various views.

Figure 1 is a side elevation of a hand- 40 power set-works, showing fragments of the operating lever and carriage. Fig. 2 is a transverse vertical section through the set shaft, carrier arm, grip-block and grip-block cap. Fig. 3 is a vertical section 45 through the carrier arms, grip-blocks, springs and grip-block caps, the section being taken on the line II-II of Fig. 2 looking in the direction of the arrow.

The set-works as disclosed, shows the 50 various operating elements in mid-position. The frame 23 is mounted on the carriage 31 in the usual manner and has bearings 30, 32, formed therein. The rock shaft 22 is supported in the bearings 32 and has the usual 55 crank disks 21 and operating lever 18 se-

cured thereto. The set shaft 1 is supported to rotate in the bearings 30 of the frame 23, and has a ratchet wheel 5 mounted thereon and secured thereto by any suitable means, such as keys 34. A pair of carrier arms 2, 4, are supported by the set-shaft 1, one on each side of the ratchet wheel 5. The carrier arms 2, 4, are free to oscillate on the shaft 1, being removable from the shaft 1 upon removal of the retaining caps 16, 17, 65 which are secured to the arms 2, 4, respectively, by means of bolts 6. The free extremities of the carrier arms 2, 4, are provided with grip-block supports 36, 37, which are preferably formed integral with the 70 body portions of the arms 2, 4. The grip-block supports 36, 37, extend over the face of the ratchet wheel 5 and have parallel-sided, radially directed openings formed therethrough.

75 The grip-blocks 11, which in the present disclosure number two to each carrier arm 2, 4, have parallel sides which closely fit the sides of the radially directed openings formed through the supports 36, 37. The 80 teeth of the grip-blocks 11 are similar in contour to those of the ratchet wheel 5. The openings in the supports 36, 37, are so located that with the teeth of one of the blocks 11 in full coaction with the teeth of 85 the ratchet wheel 5, the teeth of the other block will be in contact with the adjacent teeth of the ratchet wheel 5 along the inclined surfaces but not along the radial surfaces thereof, see Fig. 2. The object of this 90 construction is to prevent excessive return motion or slip of the ratchet wheel 5 during withdrawal of one of the grip-blocks 11 from operating position and application of another block 11 to operative position.

95 The grip-blocks 11 are provided with stems 8 which extend away from the blocks in a direction radial to the set-shaft 1, and pass through the removable grip-block caps 12. The helical compression springs 13 surround the stems 8 and coact with their outer ends against the caps 12 and with their inner ends against the grip-blocks 11. These springs 13 tend at all times to force the grip-blocks 11 radially toward the set 100 shaft 1 and wheel 5. Removable transverse lifting pins 14 pass through the outer ends of the stems 8, some distance above the caps 12. The forked grip releasing arms 7 are pivotally mounted on removable pivot pins 110

- 33, and have forked ends the prongs of which extend under the projecting ends of the lifting pins 14. The corresponding inwardly projecting ends of the arms 7 extend to a position in proximity with the releasing cams 10. The cams 10, of which there is one for each set of grip-blocks 11, are secured to stub shafts 15 which are rotatably mounted in bearings in the carrier arms 2, 4. The releasing levers 9 have their inner ends secured to the shafts 15, while their outer corresponding ends are directed toward each other to substantially span the gap between the carrier arms 2, 4.
- 15 The carrier arm 4 is connected with the crank disk 21 by means of a connecting rod 19, the end of which is removably connected with the arm 4 by a bolt 24. The carrier arm 2 is connected with the crank disk 21 by means of a connecting rod 20, the end of which is removably connected with the arm 2 by a bolt 3.

During setting operation of the mechanism, the operating lever 18 is oscillated about the rock shaft 22, causing the crank disks 21 to oscillate with a resulting reciprocation of the connecting rods 19, 20. As the pin 24 is moved forward by the connecting rod 19, the carrier arm 4 and its corresponding grip-blocks 11 are oscillating about the set shaft 1 in an anti-clockwise direction, and are effective in rotating the ratchet wheel 5. During the forward movement of the connecting rod 19, the rod 20 is being withdrawn with a resulting movement of the carrier arm 2 and its grip-blocks 11 in a clockwise or ineffective direction. Upon reversal of the movement of the operating lever 18, the reverse movement of the carrier arms 2, 4, takes place, and the grip-blocks 11 of the carrier arm 2 become effective in moving the set shaft 1 while those of the carrier arm 4 become ineffective and recede in a clockwise direction around the periphery of the wheel 5. It will thus be seen that the intermittent oscillatory movement of the operating lever 18 is transformed into continuous rotary movement of the set shaft 1.

During recession of the knees on the set 50 works and while a fresh log is being placed, it is desirable to have the set shaft 1 free to rotate without restraint in a clockwise direction. In order to so release the set shaft 1, the ratchet wheel 5 must be released by withdrawal of the grip-blocks 11 therefrom. This removal of the grip-blocks is preferably effected by bringing the operating lever 18 to mid-position and then simultaneously swinging the two releasing levers 9 so that 55 the releasing cams 10 take a substantially longitudinal rather than a vertical position as shown. This change in position of the cams 10 causes pressure against the inwardly projecting ends of the releasing arms 7. 60 This pressure separates the ends of the arms

7 and forces the forked ends of the arms 7 outwardly and away from the ratchet wheel 5. The outwardly moving forked ends of the arms 7 eventually come in contact with the ends of the transverse pins 14 and lift the stems 8 and grip-blocks 11 away from the ratchet wheel 5 against the pressure of the springs 13. The release of all of the grip-blocks 11 need not be effected simultaneously if not so desired. When the knees 75 have been brought to their proper positions, the levers 9 are returned to setting position, immediately following which the grip-blocks 11 become effective and positively lock the set shaft against further motion in a clockwise direction.

If it is desired to remove the grip-blocks 11 for inspection, it is necessary only to remove the caps 12 and pins 33, whereupon the blocks 11 may be readily withdrawn from their sockets. The formation of each individual grip-block 11 with a number of gripping teeth, provides a larger gripping area and reduces the danger of breaking of the gripping means. The use of grip-blocks 11 having plane surfaces of reaction in the carrier arms 2, 4, also eliminates the excessive wear heretofore encountered with the use of pivotal supports for the pawls, thereby providing a more accurate setting device. 90 By forming the supports 36, 37, integral with the carrier arms 2, 4, a more rigid support of the grip-blocks 11 is obtained, than by suspending the pawls from overhanging pins. It will also be observed that all of the 100 working parts of the device are readily accessible for lubrication and repairs in cases of emergency.

It should be understood that it is not desired to be limited to the exact details of construction shown and described, for obvious modifications will occur to a person skilled in the art.

It is claimed and desired to secure by Letters Patent,

1. In combination, a set-shaft, a ratchet wheel secured thereto, a carrier arm having an opening therethrough, a cap secured to said carrier arm adjacent the opening therein, a grip-block movable within said opening and having a projection formed with an abutment, and an arm engageable with said abutment for moving said grip-block away from said ratchet wheel and for retaining said grip-block within said opening, said grip-block being removable from said arm through said opening upon removal of said cap.

2. In combination, a set-shaft, a ratchet wheel secured thereto, a carrier arm having an opening therethrough, a cap secured to said carrier arm adjacent the opening therein, an arm, and a grip-block supported from said cap through said arm, said grip-block being removable from said carrier arm

through said opening upon removal of said cap.

3. In combination, a carrier arm having a recess therein, a grip-block slideable within 5 said recess and formed with abutments, a cap; and an arm, said cap being engageable with an abutment of said grip-block to limit outward motion of said block and said arm being engageable with another of said abut- 10 ments of said grip-block to limit inward mo-

tion of said block, whereby said grip-block is retained within the recess of said carrier arm at all times.

In testimony whereof, the signature of the inventor is affixed hereto in the presence of 15 two witnesses.

LEMUEL D. HANFORD.
